UNITED STATES PATENT OFFICE

STUART BALLANTINE, OF MOUNTAIN LAKES, NEW JERSEY, ASSIGNOR TO RADIO FREQUENCY LABORATORIES, INCORPORATED, OF BOONTON, NEW JERSEY, A CORPORATION OF NEW JERSEY

ELECTRICAL CIRCUITS FOR RADIORECEIVERS

Original application filed June 17, 1924, Serial No. 720,708. Patent No. 1,760,871, dated June 3, 1930.
Divided and this application filed March 10, 1928. Serial No. 260,779.

This application is a division of my co-pending application Serial No. 720,708, filed June 17, 1924, Patent 1,760,871 granted June 3, 1930.

5 The present application relates especially to electrical circuits adapted to reduce or suppress undesired effects due to capacitive coupling existing between the anode and the control electrode of a vacuum tube, or input 10 or output circuits associated therewith, as employed in an electrical repeater or amplifier circuit, stage, or the like. Circuits intended to accomplish this result have heretofore been known and used. In general, certain 15 methods of preventing retroaction comprise the introduction of an auxiliary coupling between the input and output circuits to feed back an additional current which will oppose the effects of undesired retroactive 20 currents, the introduction into one of the audion circuits of sufficient resistance to render the stage stable, or the use of untuned or aperiodic circuits.

An object of the present invention is to 25 provide an amplifier stage which will suppress the effects of retroactive currents over an extended range of frequencies. More specifically an object of the invention is to provide improved forms of anti-regenerative circuits in which the path taken by the retroactive currents and/or the compensating currents includes a resistance.

These and other objects of the invention will be apparent from the following specification 30 when taken with the accompanying drawings, in which

Fig. 1 is a circuit diagram showing an audion repeater element with arrangements for rendering it unidirectional, the effects of capacity coupling being eliminated by a compensation method;

40 Fig. 2 is a circuit diagram showing an audion repeater element with arrangements for rendering it unidirectional, the effects of capacity coupling being eliminated by a neutralization method;

45 Fig. 3 is a circuit diagram showing an audion repeater element with arrangements for rendering it unidirectional, the effects of

capacity coupling being eliminated by a modified neutralization method.

In the circuit shown in Fig. 1, the general method employed to compensate for the effects of capacity coupling has been described 55 in my copending application, Serial No. 629,702, filed April 3, 1923.

L_1 and L_2 constitute the input transformer tuned by means of the variable condenser C_2 . Any other suitable input arrangement may be 60 made. The output transformer is formed by L_4 and L_5 which are tuned by C_3 . The circuits may be energized from any suitable source such as the usual A, B and C batteries or the like. A filament control resistance R 65 is included in the filament circuit and may also serve in biasing the grid negatively. A filament shunting condenser of low impedance, C_1 , may be connected across the filament terminals to introduce alternating current 70 plate current through both filament terminals. C_c represents a compensating capacity which may obviously reside between the electrodes of the audion or their connecting wires or in an external condenser.

75 The undesired coupling between the input circuit and the output circuit arises, in part at least, from the capacity C_m . As described in my copending application, Serial No. 629,702, the effects of such capacity coupling 80 may be reduced or eliminated by bringing point Y of the input circuit to the alternating current potential of a point X in the output circuit. Point Y is the lower terminal of the input circuit, that is, the terminal having the 85 lower alternating current potential, or, in general, most closely approaching to the alternating current potential of the filament. The lower terminal Y of the input circuit is brought to the potential of point X by means 90 of an extra winding or coil L_6 which is inductively coupled to the plate impedance L_4 , for example, at the lower end thereof, as shown. In certain cases it is desirable to add compensating resistances R_1 and R_2 to either C_m 95 or C_c , or both, either in series, as shown in Fig. 1, or in parallel.

In Fig. 1 the upper terminal of the input circuit may thus be connected to the filament through the serially connected resistance R_1 100

and capacity C_e , and to the audion grid through resistance R_2 . The network has the form of an alternating current Wheatstone bridge which, when balanced, operates to counteract the effects of retroactive currents flowing to the grid and the input circuit through capacitive coupling between the output and input circuits such as the capacity C_m . A compensating current is impressed upon the lower terminal Y by the added winding L_6 . The compensating resistance R_1, R_2 may perform several functions, and, according to the constants of other elements of the amplifier stage, any or all of the effects of these resistances may be important in any particular circuit. These resistances may effect an adjustment of phase relation between the retroactive currents and the compensating currents, and they may also compensate for the resistance component of the variable space charge coupling. The resistance R_2 may also function as a "losser", since it is serially connected between the tuned input circuit and the grid on the audion.

Fig. 2 illustrates a repeater unit in which the audion capacity coupling is eliminated by a neutralization method. The principle of such methods is disclosed in my copending applications, Ser. No. 629,702, filed April 3, 1923, and Ser. No. 167,701, filed February 12, 1927. Referring to Fig. 2, L_1 and L_2 constitute the input transformer which is tuned by the condenser C_2 ; C_e is a compensating condenser; L_3 and L_4 are either separate coils or parts of the same coil; L_5 and C_3 represent the output circuit; R_e is a compensating resistance; R is a resistance in the filament circuit, the direct current drop across which is used to give the grid a suitable negative bias; the "C" battery reinforces the biasing effect of R ; the "A" and "B" batteries have their conventional circuit locations; C_1 is a filament-shunting condenser of low impedance. The output circuit, represented by the coil L_5 must be coupled to L_3 and L_4 so that the effective impedances between the terminals of L_3 and L_4 are of proper value to maintain a state of balance in the circuit, obviously also the coupling between L_3, L_4 and L_5 must be fixed. It is not necessary that L_3 and L_4 be coupled together, but their couplings to L_5 must result in impedances between their terminals which satisfy the requirements of neutralization. For best results, with tubes of the usual 15,000 ohms plate resistance, as now constructed, the coil L_3 and L_4 are of small inductance compared with that of L_5 and the coupling between L_3 and L_5 and between L_4 and L_5 should be close. In order that persons skilled in the art may reproduce my results, I give the following constants of one specific circuit: $L_3=20$ microhenries; $L_4=20$ microhenries; $L_5=300$ microhenries; $C_3=0.00033$ microfarads; $C_e=0.000005$ microfarads. These values were found suitable

for a unit designed to cover a wave length range of 200 to 600 meters.

Fig. 3 illustrates a repeater unit in which an alternative method of neutralizing the audion capacity coupling is employed. This method is disclosed in my copending applications above referred to, and in substance in Hazeltine U. S. Patent 1,489,228, April 1, 1924. The other arrangements for eliminating the enumerated couplings other than that due to the audion capacity, are those already described. L_1 and L_2 are two coils of preferrably tight coupling wound in opposite directions and so connected that their non-common terminal voltage are opposite in phase; C_e is a compensating condenser; R_1 and R_2 are compensating resistances, which make up the departure of the voltages of L_1 and L_2 from exact 180° phase relationship and which also compensate for the resistance component of the variable space charge coupling; R is a filament resistance, the drop across which helps to bias the grid negatively; the battery "C" also has this function; C_1 is a filament-shunting condenser of low impedance; the batteries "A" and "B" have their conventional functions; L_3 and L_4 constitute the output transformer, tuned by the condenser C_4 .

Various modifications of the specific circuits herein described, and equivalent arrangements thereof, fall obviously within the scope of my invention. For example, arrangements in which the compensating or phase-adjusting resistances are wholly or partially embodied in one or more elements of the compensating circuit, as the compensating inductance or capacity, are contemplated by me, and fall within my invention. Moreover, my invention extends to the control of the resistance balance of the circuit in either direction, and is not limited to a circuit which is perfectly balanced.

I claim:

1. An electrical amplifier circuit comprising, in combination, a vacuum tube including at least anode, cathode, and control electrode elements; a tuned input circuit for said vacuum tube; an output circuit for said vacuum tube; a connection including a resistance between the high potential terminal of said input circuit and the control element of said vacuum tube; and means operative to reduce the effects of retroactive currents due to coupling between said input and output circuits.
2. An electrical amplifier circuit comprising, in combination, a vacuum tube including at least anode, cathode, and control electrode elements; a tuned input circuit for said vacuum tube and an output circuit therefor, said circuits having capacitive coupling between them; a resistance connected between the high potential terminal of said input circuit and the control electrode of

5 said vacuum tube; and compensating means operative between said input and output circuits and including a coil electromagnetically coupled to a coil in one of said circuits and coupled to the other of said circuits by capacitive impedance.

3. An electrical amplifier circuit comprising, in combination, a vacuum tube including at least anode, cathode, and control electrode 10 elements; a tuned input circuit for said vacuum tube and an output circuit therefor, said circuits having capacitive coupling between them; a resistance connected between the high potential terminal of said input circuit and the control electrode of said vacuum tube; and compensating means operative between said input and output circuits and including a coil electromagnetically coupled in the reverse sense to a coil in one of said 15 circuits and coupled to the other of said circuits by capacitive impedance.

4. An electrical amplifier circuit comprising, in combination, a vacuum tube including at least anode, cathode, and control electrode 20 elements; a tuned input circuit for said vacuum tube and an output circuit therefor, said circuits having capacitive coupling between them; a resistance connected between the high potential terminal of said input circuit and the control electrode of said vacuum tube; and a compensating circuit including a coil electromagnetically coupled in the reverse sense to a coil in one of said circuits and capacitively coupled to the other of said 25 circuits.

5. An electrical amplifier stage comprising a vacuum tube, a tuned input circuit and an output circuit having capacitive coupling between them, a compensating circuit including a capacity and inductance connected in series between said input and output circuits, and a resistance connected between the high potential terminal of said input circuit and the grid of said vacuum tube.

45 6. An electrical amplifier circuit comprising, in combination, a vacuum tube including at least anode, cathode, and control electrode elements; a tuned input circuit for said vacuum tube and an output circuit therefor, 50 said circuits having capacitive coupling between them; a resistance connected between the high potential terminal of said input circuit and the control electrode of said vacuum tube; and a compensating circuit including a coil electromagnetically coupled in the reverse sense to a coil in said input circuit and capacitively coupled to a point in said output circuit.

7. An electrical amplifier circuit comprising, in combination, a vacuum tube including at least anode, cathode, and control electrode 55 elements; a tuned input circuit for said vacuum tube and an output circuit therefor, said circuits having capacitive coupling between them; a resistance connected between

the high potential terminal of said input circuit and the control electrode of said vacuum tube; and a compensating circuit connected between said input and output circuits and including, in series, a coil electromagnetically coupled in the reverse sense to a coil in said input circuit, a capacity and a 70 resistance.

8. An electrical amplifier stage of the type which includes a vacuum tube and tuned input and output circuits associated therewith having coupling therebetween whereby undesired retroactive currents are set up, and in which the effects of said retroactive currents are opposed by additional currents flowing between said input and output circuits; characterized by the fact that a resistance is connected between the high potential terminal of said input circuit and the control element 75 of said vacuum tube.

9. An electrical amplifier stage of the type which includes a vacuum tube and tuned input and output circuits associated therewith having coupling therebetween whereby undesired retroactive currents are set up, and in which the effects of said retroactive currents are opposed by additional currents flowing between said input and output circuits; characterized by the fact that a resistance of 80 such value as to produce an adjustment of phase relation between said retroactive currents and said additional currents is connected between the high potential terminal of said input circuit and the control element of said vacuum tube.

10. An electrical amplifier circuit comprising, in combination, a vacuum tube including at least an anode, a cathode, and a control electrode; a tuned input circuit including an input transformer having a tuned secondary winding associated with said cathode and said control electrode; an output circuit including an output transformer having a primary winding associated with said cathode and said anode and a tuned secondary winding; a resistance connected in series between the high potential terminal of said tuned secondary winding of said input transformer and said control element of said vacuum tube; and compensating means associated with said input and output circuits and including capacitive impedance arranged to permit the flow of anti-regenerative currents of such phase and amplitude as to oppose regenerative currents flowing through inherent capacitive coupling between said input and output circuits.

In testimony whereof, I affix my signature.
STUART BALLANTINE.
